Primary Examiner — Susan Bennett Hattan*Assistant Examiner* — Suzanne E Tisdell(74) Attorney, Agent, or Firm — Katten Muchin Rosenman LLP(57) CLAIM

The ornamental design for manufactured home, as shown and described.

DESCRIPTION

FIG. 1 is a front, left-side perspective view showing a second embodiment of the manufactured home.

FIG. 2 is an elevation front view of the second embodiment of the manufactured home.

FIG. 3 is an elevation back view of the second embodiment of the manufactured home.

FIG. 4 is an elevation left-side view of the second embodiment of the manufactured home.

FIG. 5 is an elevation right-side view of the second embodiment of the manufactured home; and,

FIG. 6 is a top plan view of the second embodiment of the manufactured home.

The broken lines form no part of the claimed design.

1 Claim, 5 Drawing Sheets(56)
